The ornamental design for an infrared camera, as shown and described.

DESCRIPTION

FIG. 1 is a top, front perspective view of an infrared camera showing my new design;

FIG. 2 is a bottom perspective view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is a top plan view thereof.

The broken lines in the drawings are shown to illustrate the portions of an infrared camera in which the design is embodied and form no part of the claimed design. The dash-dot lines denote the boundary of the claim and form no part of the claimed design.
